GLOVE

Elmer T. Ceder, Minneapolis, Minn.

Application November 19, 1952, Serial No. 22,372

Term of patent 14 years

(Cl. D3—11)

Fig. 1

Fig. 2

Fig. 1 is a top plan view of a glove, showing my new design; and

Fig. 2 is a side elevational view thereof.

The undisclosed back of the glove is similarly unornamented and presents a similar appearance as the view shown in Figure 1.

The characteristic feature of the glove is shown in full lines in the drawings.

I claim:

The ornamental design for a glove, substantially as shown and described.
